UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, A CORPORATION OF MASSACHUSETTS.

METHOD OF METAL-DRAWING.

1,200,309.

Specification of Letters Patent.

Patented Oct. 3, 1916.

Application filed August 2, 1915. Serial No. 43,084.

To all whom it may concern:

Be it known that I, HJALMAR G. CARLSON, a citizen of the United States, residing at Worcester, in the county of Worcester 5 and State of Massachusetts, have invented a new and useful Method of Metal-Drawing, of which the following is a specification.

This invention relates to a method of producing a hollow article of sheet metal which 10 I will call a shell and which may be used for many purposes in accordance with its particular size and shape. A characteristic feature of the article, however, is that it varies in thickness from its closed end to its 15 open end, being thicker at the open end. Also it may have in addition an integral enlargement at its open end formed by the thickening process instead of being doubled over or creased so that it has no internal 20 seam.

The principal objects of the invention are to provide a method of producing an article such as above described, and particularly to 25 provide means whereby by a simple drawing operation the open end of a shell-shaped article can be thickened and the closed end reduced in thickness at each drawing operation so that by a series of successive drawing 30 operations of this character an article can be produced which will have a materially thickened open end; also to provide in co- 35 operation in these series of drawing operations other steps by which the closed end is reduced in thickness and the article is finally shaped up to the desired definite shape.

Reference is to be had to the accompanying drawings, in which,

Figure 1 is a transverse sectional view of a die showing a plunger in position 40 for performing the first operation; Fig. 2 is a similar view showing the second operation; Fig. 3 is a sectional view of a different form of die and a plunger showing the operation of reducing the thickness 45 of the end of the blank; Figs. 4, 5 and 6 are views similar to Figs. 1 and 2 showing three other specific steps of the same character as those illustrated in Figs. 1 and 2; Fig. 7 is a similar view showing the first 50 step of the method of bringing the blank up to a definite shape after the preliminary operations shown in the first six figures; Fig. 8 is a similar view showing the completion 55 of this step, and Fig. 9 is a side view of the completed article.

This invention is designed for the production of a shell having a cylindrical surface inside, provided with a closed end and an open end, and having the metal thicker at its open end than at its closed end and growing so progressively from one end to the other. Heretofore, these articles have been formed by machine operations and have been made in a comparatively expensive manner. I have discovered that such an article can be made with equal accuracy by simple drawing operations, thus reducing its expense by a very great percentage and I have also discovered a principle of metal drawing which can be used in this method 60 to advantage, namely that when a blank is drawn through a smaller die by means of a plunger smaller in diameter than the internal diameter of the blank at all stages of the 65 said drawing step, the drawing operation 70 will have the effect of drawing out the blank as would be expected, but in addition thereto, has the further effect of thickening the open edge of the blank. This thickening effect progresses substantially uniformly 75 from the closed to the open end, especially after the blank has been subjected to a number of these operations. Furthermore, I 80 find that an enlarged shoulder at the open end of the blank can also be formed practically by this operation, so that the complete article is homogeneous throughout and has no line of cleavage formed by folding the 85 metal on itself, as would be the case if it were formed by the usual sheet metal working 90 operations.

Referring now to the drawings, the first 95 step in the process is to take a flat blank and place it on top of a die 10 which has a perforation or opening 11 of a shape corresponding with the shape of the desired article; in this case circular. This opening also is smaller than the diameter of the flat blank which is to be operated upon. This flat 100 blank is forced into the die and preferably through it by a plunger 12 which is cylindrical in form. The blank *a* which is being operated upon is thus forced into the shape shown in this figure, but it is to be observed 105 that the diameter of the plunger is slightly less than the diameter of the die opening 11, diminished by twice the thickness of the blank. In other words, it is sufficiently small so that, while centered perfectly in 110 the opening 11, it will not touch the inner

circular walls of the blank at its closed end. The result of this operation is to draw the metal of the blank so as to elongate it and to fold in the outer edge of the blank so that this edge is slightly thickened. As a matter of fact, the inner edges of the blank may or may not come into contact with the plunger 12. If it does, the plunger smooths it on its inner surface. It will be understood that in the usual method of drawing, in which the plunger 12 would be slightly larger than in this case, that is large enough to touch the blank at all points, there would be the same tendency to thicken the blank but it could not take place because all the space is filled, consequently the blank would be elongated to a greater degree and would not be thickened.

The cup-shaped blank a having been produced in accordance with the arrangement shown in Fig. 1, it is then placed in a second die 20 and forced through it by a plunger 22. The relation between this die and plunger is the same as that between the first named die and plunger and the effect is the same, that is a blank a' is produced having a further elongation and smaller diameter and its edge is thickened still further. It is found in practice that this thickening extends substantially from the open to the closed end of the blank so that the blank may be considered as having a conical inner surface, although it is not a perfect cone. The blank is thereafter subjected to a succession of these operations in a series of dies and plungers all having the same relation to each other, as has been described, and a series of blanks a^2 , a^3 , and a^4 is obtained, each one smaller and longer than the one from which it is made and thicker at its open edge. The dies and plungers operating on the blanks a^2 , a^3 , and a^4 are designated respectively 30, 40, 50 and 32, 42 and 52. At an intermediate point in this process, preferably after the operation shown in Fig. 2, and before that shown in Fig. 4, the closed end of the blank is flattened and thinned by subjecting the blank to pressure between a flat bottomed die 23 and a plunger also having a flat bottom. This plunger may be if desired made of exactly the same shape and size as the plunger 22 and may in fact be the same one as indicated. If desired, the die 23 can be located just below the die 20 and receive the plunger and blank as soon as the latter is freed from the die 20 by passing entirely through it.

It will be understood that the number of operations above described will depend upon the article being produced and the metal of which it is produced and that this method is not limited to any particular number of such operations.

After the blank has been brought to the condition shown at a^4 in which it is of sub-

stantially the diameter and length desired, the rough, thickened open end is squared off by any desired means, and then it is put through the finishing operations, as shown in Figs. 7 and 8. In Fig. 7 it is shown as being forced into a die 53, which instead of having a cylindrical passage therethrough, is provided with a cavity having three cylindrical portions 54, 55 and 56 of different sizes. The blank is forced into this die by a plunger 57 which is cylindrical throughout and has an enlarged part 58 with a square shoulder. The die 53 is shown as consisting of two parts but that is not essential. The result of this operation is to produce a blank a^5 and especially to form its interior into a true cylindrical form throughout most of its length and bring the variation on the outside, preparatory to making it conical in form on the exterior. At the top the inside is not shaped definitely, but it is gaged to length by the square shoulder and somewhat thickened at the top preparatory to forming a projecting shoulder.

The next operation shown in Fig. 8 consists in forcing the blank into a die 60 having a conical surface 61 and an enlarged cylindrical surface 62. This is done by means of a plunger 63 of cylindrical form throughout and having an enlarged head 64 provided with a flat lower surface. The result of this operation is to finish the shell a^6 so as to give it a complete true cylindrical inner surface, a true conical outer surface, and an enlarged cylindrical shoulder at the top having a square end. Upon being removed from this die and plunger, the shell is ready for any machining operations such as providing the screw-threads a^7 , on the shoulder of the shell a^6 .

From this description it will be seen that a shell is secured which is thinner at its closed end than anywhere else and progressively grows thicker toward its open end and yet it is cylindrical inside and a true conical shape outside. Furthermore, it is provided with an enlarged shoulder for receiving the screw-threads a^7 formed gradually by the die pressing and drawing operations, and finally shaped up by the finishing operations without folding any metal on itself and thus without providing a seam within it. In this way an article is secured having a maximum strength and of a maximum degree of perfection throughout, and yet the method of producing it is so extremely expeditious that when a large number of articles are to be produced it can be done in a most inexpensive manner and without waste of stock except such as is involved in cutting out the first flat blank from a sheet of metal.

Although I have illustrated and described a certain number and sequence of steps and

shown the method as applied to the production of a specified article, I am aware of the fact that the invention is not limited in these respects and therefore I do not wish 5 to be so limited except as set forth in the claims.

Having described the invention what I claim is:—

1. The method of drawing metal which 10 comprises forcing a blank through a die by means of a plunger, leaving a space between the die and plunger around the latter slightly greater than the original thickness of the metal, whereby the metal for a distance from 15 its edge will buckle upon itself and thicken but will be shaped and drawn out between the die and plunger and the metal near the other end of the blank will be shaped by the die but will be spaced from the plunger.
  2. The method of drawing out and upsetting a cup-shaped blank, which comprises forcing the cup-shaped blank through a die by means of a plunger so as to cause the metal along a portion of the cylindrical part 25 to buckle on itself and thicken, causing the metal to remain in contact with and be shaped by the plunger at a distance from its closed end so as to draw the thickened metal out to a thickness greater than its 30 original thickness at that region, whereby the inside diameter of the blank will be left greater at the closed end than at the open end.
  3. The method of drawing metal which 35 comprises forcing a blank through a die by means of a plunger, leaving a space between the die and plunger around the latter slightly greater than the original thickness of the metal, whereby the metal for a distance from 40 its open edge will buckle upon itself and thicken but will be shaped and drawn out between the die and plunger, and thereafter forcing the formed blank through a second die by means of a plunger for reducing the 45 diameter of the blank and leaving a space between the die and plunger slightly greater than the maximum thickness of the first named formed blank, whereby the buckling, thickening and drawing operation will be 50 repeated.
  4. The method of drawing out and upsetting a flat blank which consists in forcing the flat blank through a die by means of a plunger to cause the metal along the edge
- of the blank to buckle on itself, causing it 55 to thicken at the edge and to assume a cylindrical form in contact with the surface of the die and at the same time causing the metal near said edge of the blank to remain in contact with and be shaped by the 60 plunger so as to draw the thickened metal out to a greater thickness than it originally had at that point and leaving a space between the end of the plunger and blank to allow the cross section of the blank at the 65 end to remain less than at the edge.
5. The method of drawing metal which 70 comprises forcing a blank through a die by means of a plunger, leaving a space between the die and plunger around the latter slightly greater than the original thickness of the metal, whereby the metal for a distance from 75 its edge will buckle upon itself and thicken but will be shaped and drawn out between the die and plunger, whereby the 80 blank is given a uniform outside shape from end to end, but its inside diameter at the closed end is greater than it is at its open end, squaring off the open end and then simultaneously drawing out the closed end of the blank, shaping it to a uniform inside diameter nearly to its open end and gaging it for length.
6. The method of drawing metal which 85 comprises forcing a blank through a die by means of a plunger, leaving a space between the die and plunger around the latter slightly greater than the original thickness of the metal, whereby the metal for a distance from 90 its edge will buckle upon itself and thicken but will be shaped and drawn out between the die and plunger, whereby the blank is given a uniform outside shape from end to end, but its inside diameter at the closed end is greater than it is at its open end, 95 squaring off the open end and then simultaneously drawing out the closed end of the blank, shaping it to a uniform inside diameter nearly to its open end and further enlarging its open end to form an integral 100 seamless shoulder.

In testimony whereof I have hereunto set my hand, in the presence of two subscribing witnesses.
